(57) **CLAIM**

The ornamental design for multifunctional multimeter, as shown and described.

DESCRIPTION

FIG. 1 is a front elevational view thereof;

FIG. 2 is a rear elevational view thereof;

FIG. 3 is a top plan view thereof;

FIG. 4 is a bottom plan view thereof;

FIG. 5 is a left side elevational view thereof; and,

FIG. 6 is a right side elevational view thereof.

The broken lines in the drawings are for the purpose of illustrating portions of the multifunctional multimeter that form no part of the claimed design.
